UNITED STATES PATENT OFFICE.

MILON JAMES TRUMBLE, OF ARTESIA, CALIFORNIA, ASSIGNOR, BY MESNE ASSIGNMENTS, TO SIMPLEX REFINING COMPANY, A CORPORATION OF CALIFORNIA.

PROCESS AND APPARATUS FOR MAKING ASPHALTUM.

1,182,601.

Specification of Letters Patent.

Patented May 9, 1916.

Application filed September 16, 1912. Serial No. 720,687.

To all whom it may concern:

Be it known that I, MILON JAMES TRUMBLE, a citizen of the United States, residing at Artesia, in the county of Los Angeles and State of California, have invented a new and useful Process and Apparatus for Making Asphaltum, of which the following is a specification.

In the ordinary process of making asphaltum from natural oil or bituminous materials, the same is subjected to heat in a closed vessel or still, and the more volatile oils or constituents are vaporized and carried off through a vapor outlet, the entire process of reducing the volatile constituents being carried on in the one still until the asphaltum has reached the desired degree of hardness. I am aware that air as well as steam has been commonly used in such operation to aid or hasten the carrying off of such volatile oils. In all such instances, however, it is necessary to raise the temperature to a high degree and when it is desired to produce asphaltum from asphaltic oils, such as those produced in California, of a hardness suitable for street pavement work, the temperature is often raised to from 700 to 900 degrees F. In the operation just described great care must be exercised by the still operator to prevent burning of the asphaltum or producing a "cracking" thereof and the attendant liberation of free carbon, and furthermore owing to the difference in treatment, time of treatment and the inability of the still man to sample the product in the still to determine its condition, it is generally impossible to get any two batches of asphaltum from the stills in the same condition; one still run will vary from another in density as proven by the penetration test, but generally the greatest obstacle is the presence of free carbon in the product which, if present to any degree, destroys the life of the asphaltum and makes it "short" or low in ductile qualities. Furthermore in the ordinary manner of treatment from 36 to 60 hours' time is required to finish a still of asphaltum. Generally such stills are soon blistered upon the bottom from being subjected to such high temperature for such a long period of time, and when so blistered must

be put out of commission until they are repaired by patching.

One object of my invention is to provide a process for making asphaltum which will not require high temperatures in the production thereof and which will not require that the material be subjected to the heat for any great length of time.

Another object of my invention is to provide a process for making asphaltum in which such asphaltum will be free from free carbon.

Another object of my invention is to provide a process for making asphaltum continuously and enable the operator at any time to ascertain the character of the product and therefore produce a regular and uniform grade of asphaltum.

Another object of my invention is to provide a process for making asphaltum which can be so varied or regulated as required to produce any quality of asphaltum desired without altering the temperature of the heating agent.

Another object of my invention is to provide an apparatus for producing asphaltum continuously and of any grade desired, free of free carbon and at a less expense than heretofore required.

Another object of my invention is to provide an apparatus for making asphaltum which will be cheap to install and operate and which will have great capacity.

My invention in part consists in heating the asphaltum base material in a closed retort to a temperature sufficient to volatilize the major portion of the lightest vaporizable oils contained in the crude or base material, admitting such base material to an expanding chamber and maintaining the temperature thereof and finally allowing the said material to flow over a heating medium for a distance and injecting steam into the flowing mass to carry off any remaining oils desired.

My invention in part also consists in providing an apparatus whereby a body of flowing asphaltum base material may be heated under confinement, introduced into an expanding chamber where a portion of the vapors are drawn off and finally caused to travel for a considerable distance during

which travel the material is subjected to the refining action of steam to drive off the vapors desired.

The accompanying drawings illustrate 5 the apparatus which I have found in practice to be best fitted for carrying out my invention.

Figure 1 is a vertical section of the apparatus. Fig. 2 is a perspective view of 10 the reducer, the greater portion of the top and floor of vapor chambers being removed to show the interior. Fig. 3 is a vertical cross section of the reducer taken on line x^3-x^3 Fig. 1.

15 The asphaltum material to be treated is heated to the desired temperature in the prime heater 1 which, as shown, consists of two tubular retorts 2 and 3 which are connected by suitable pipe at one end so that 20 the material introduced into retort 2 flows therethrough and into retort 3 from which it passes by means of pipe 4, through the vapor column 5 and delivers into the top of the evaporator 17.

25 The form of evaporator herein shown differs slightly from that disclosed in United States Letters Patent No. 996,736 issued July 4th, 1911. The evaporator is arranged vertically in the stack or flue 16 of the 30 prime heater so that the temperature of the material in the evaporator is raised to a sufficient degree to drive off the greater percentage of the volatile oils. The material flowing into the evaporator through the conductor 4 is deflected by the hood 18 which operates to distribute it in a thin film over the walls of the evaporator, in which condition the volatile oils are readily liberated. Equalizing spreaders 23 are supported centrally in the evaporator upon the vapor outlet pipe 24, which is provided with apertures 25, occurring beneath the spreaders, to 35 allow the passage of the vapors into the pipe 24, from which they are conducted 40 through the vapor legs 26 into the vapor column 5.

The material from which the vapors have 45 been liberated, passes downwardly over the walls of the evaporator and is collected in 50 the bottom 27 thereof, from which it is drawn by the pipe 28 and passes into the header 29. Connected to the header 29 are a plurality of conductors 30 provided with valves 31 so that the amount of material 55 passing through the various conductors 30 may be regulated.

The reducer 32, as shown, consists of a 60 rectangular structure of sheet metal having the lower part thereof subdivided into six 65 intercommunicating compartments, such as 33, 34, 35, 36, 37 and 38, such compartments being formed by the side walls 39 and 40 and walls 41, 42, 43, 44 and 45 and the bottom 46 and floor 47 of the vapor chambers 65 48 and 49. The heating pipes 30 pass lon-

gitudinally through the reducer, one of such pipes lying within each of the compartments, and head into a collecting head 50 at the opposite end of such reducer to that upon which is located the header 29.

A T 51 is provided at one end of the header 50, and a pipe 52 leads from such T into the delivery pipe 53 which delivers the material into the first compartment 33 of the reducer. A valve 54 in pipe 53 is provided to regulate or control the passage of material through the pipe 53 into the reducer. A pipe 55 leads from the T 51, whereby the material may be cut directly into a tank without passing through the reducing process as when making road oils. A valve 57 is arranged to control the passage of material through such pipe 55.

A steam header pipe 58 having a plurality of steam pipes 59 heading thereinto is arranged at one end of the reducer and furnishes steam to each of said pipes 59. Said steam pipes are perforated along their length and enter the reducer through one end thereof and traverse the several compartments longitudinally and deliver steam thereto. Preferably such steam pipes are arranged parallel to the heating pipes 30 and are slightly above the same, but the same may be arranged beneath such heating pipes 30 and thereby accomplish the end attained by my invention. Valves 60 are provided, one for each steam pipe 59, to regulate the amount of steam delivered into the several compartments.

The hot material flowing outwardly from the bottom of the evaporator through pipe 28 is conducted into the header 29 from which it is fed to the several heating compartments 33, 34, 35, 36, 37 and 38 heats the same, and by so doing gives up a certain amount of heat, and when delivered back into compartment 33 by pipe 53 is ready to again absorb heat from the heating pipe lying within that compartment. Upon being admitted to such compartment 33 the material flows the full length thereof and fills the same up to the level of the perforation 61 in the wall 41 and flows the length of the compartment 34 and overflows through opening 62 in wall 42. During the time such material is traversing the several compartments, it is in constant contact with the several heating pipes 30 and the temperature of such material is maintained. Steam is admitted to each compartment through the pipes 59 which are perforated throughout their entire length within the compartments. The steam is supplied at a temperature equal to or slightly higher than the temperature of the material in the conductors 30, so that it assists in maintaining the temperature of the material in the compartments. The steam acts to agitate the material and serves as a vehicle to carry off the oils in the mate-

rial. The higher the degree of temperature of the steam the quicker the action of reducing and the consequent carrying off of the oils which soften the asphaltum. The material flows from compartment to compartment throughout the entire series thereof, if desired, and is treated in each compartment to the action of the steam from each of the several steam pipes and is also heated by the several heating pipes and the reduced material is drawn finally from compartment 38 by pipe 63.

An outlet 64 Fig. 3 from compartment 34 is provided, through which all or a portion of the material being treated may be drawn when it is desired to produce a soft asphaltum, such as that which is commonly called a heavy road oil or flux. A like outlet 65 is provided from compartment 36 from which all or a part of the asphaltum may be drawn when a product of more asphaltum contents is required than that from outlet 64.

The steam passing into each of the several compartments through the perforated pipes 59 rises through the material being reduced and carries off the volatile oils in the asphaltum and passes upwardly into its corresponding vapor chamber through the vents 22 in the floor 47 of such vapor chambers. Any condensate within such vapor chambers is drawn off by means of drain pipes 66 and 67.

Vapor pipes 68 Fig. 2 having three legs 69, 70 and 71 are arranged to carry off the vapors from the vapor chambers 48 and 49 and convey them through a cooling device 80 which consists of the vapor pipe 68 arranged centrally within a pipe 72. The space between such vapor pipe 68 and pipe 72 is filled by means of inlet 73 with a cooling liquid, such as water.

A jacket pipe 74 Fig. 1 surrounds the vapor line 75 which receives its vapor from the vapor column 5. The space between such pipe 74 and vapor line 75 is filled with the oil or other material to be reduced, by means of inlet 76, and when oil is supplied to inlet 76 the same flows through pipe 74 to the outlet 77 and through pipe 78 into the jacket 79 which receives the hot finished material flowing from the reducer through either of the outlets 64 or 65 or from the outlet pipe 63. Thus it will be observed that the oil or other material being fed to the retort heaters is first caused to absorb heat from the hot vapors flowing from the evaporator and then to absorb heat from the hot treated asphaltum, and during its passage and contact with the pipes carrying the two above mentioned heated mediums, the oil or material becomes heated to a degree nearly sufficient to throw off the required amount of volatile oils and does not require a great amount of heat from the

first which is supplied to retort tubes 2 and 3.

The several compartments 33, 34, 35, 36, 37 and 38 form with the perforation through the several walls 41, 42, 43, 44 and 45 a long narrow canal or course which is traversed by the flowing material to be reduced and while flowing through such course it is caused to travel over the hot pipes 30, whereby the temperature is maintained, and by subjecting such flowing material to the action of steam from the steam pipes the same is agitated and the volatile oils, such as the neutral or lubricating oils, are carried off by the steam as the material progresses along the course. The reducing action of the treatment may be continued throughout the entire length of the several compartments or may be arrested at either of the outlets 64 or 65 according to the character of asphaltum desired.

In actual practice I have found that heating an asphaltum oil of 12 degrees B. gravity to a temperature of 500 degrees F. in the retorts and taking off the lighter vapors in an evaporator of the character shown and described that the remainder thereof is readily reduced to hard asphaltum by passing the same through a reducer such as shown having six compartments each twelve feet in length, or in passing such material over about seventy-two feet of heater pipe and meanwhile subjecting such flowing body to the agitating action of steam. Furthermore, I believe myself to be the first to progressively treat a moving body of asphaltic material to reduce the same to the asphaltic contents desired, and I consider that my invention includes any and all forms of treatment of asphaltum containing materials where the same is reduced progressively while traversing any channel or conduit.

Air may be substituted for steam as the reducing agent within the reducer compartments, and I desire to be understood as including its use as a substitute for steam as being within the scope of my invention, but I have found that by the use of steam as the reducing medium that the asphaltum produced is of a much better quality than that produced by air.

By the term "reducing device" herein used I mean to include any form of means wherein the asphaltic material is relieved from pressure and allowed to become freed from its expanded vapors, and by the use of the term "closed conduit" I intend to define that portion of the apparatus through which the primarily heated asphaltic base material is passed, up to the point of its release, before being passed over the heating medium.

What I claim is:—

1. An apparatus for the manufacture of asphaltum from an asphaltum base material,

- comprising an evaporator, means for feeding a base material thereto, means for heating the same to liberate vapors therefrom, a vapor outlet, an asphaltic material outlet, 5 a reducing device, a closed conduit for conveying the material to and through said device, a prolongation of said conduit beyond the reducing device arranged to discharge the material into the device and permit it to flow over the conduit whereby the 10 temperature of the material is maintained, means for liberating vapors from the material and means for conveying them from the reducing device.
- 15 2. An apparatus for the manufacture of asphaltum from asphaltum base material, comprising means for heating the material to liberate vapors therefrom, a reducing device, a closed conduit for conducting the hot material through the reducing device, a prolongation of said conduit arranged to discharge the material into the reducing device and permit it to flow in contact with the closed conduit whereby its temperature is 20 maintained, means for admitting steam below the surface of the material in the reducing device whereby the material is agitated and vapors are liberated therefrom.
- 25 3. In an apparatus for the manufacture of asphaltum from an asphaltum base material, a heater, means for supplying such heater with a constant supply of material, an evaporator, means for conveying a material from the heater to such evaporator, a vapor outlet from the evaporator, outlet means from the evaporator for the asphaltic material, a reducer adjacent to such evaporator, means for conducting the asphaltic material from the material outlet of the evaporator to the reducer, means for conducting 30 the hot asphaltic material through the reducer to impart heat thereto, return means for returning the asphaltic material to the reducer, whereby the same may flow over the conducting means, and means for admitting a reducing agent into the flowing asphaltic material whereby the volatile oils are removed therefrom progressively as such material proceeds through the reducer.
- 35 4. In an apparatus for the manufacture of asphaltum from an asphaltum base material, a heater for such material, means for furnishing a steady supply of heated material from such heater, an evaporator 40 adapted to receive the heated material from the heater, outlet means from the evaporator, a reducer adjacent to such evaporator, and means for conveying the unevaporated material from the evaporator to the reducer, a plurality of intercommunicating compartments in the reducer, means for conducting a portion of the hot asphaltic material through each of such compartments, means for delivering such material into one of the 45 compartments to flow over the conducting 50 means within such compartment, means for admitting a reducing agent along such compartment and within the body of flowing asphaltic material and outlet means from such compartment to permit the escape of the reducing agent and the volatile oils carried thereby.
- 55 5. In an apparatus for the manufacture of asphaltum from an asphaltic base material, a heater adapted to supply a constant supply of hot asphaltic base material to be reduced, an evaporator arranged to receive the supply from the heater, and liberate a portion of the volatile oils therefrom, a reducer adjacent to such evaporator and 55 adapted to receive such material therefrom, a conduit within the reducer adapted to receive the asphaltic material from the evaporator and to permit the same to flow therewith, a heating medium within the channel arranged to heat the flowing asphaltic material, and means for admitting a reducing liquid below the surface of the flowing asphaltic material whereby the remaining volatile oils in the material are progressively carried off as the material progresses along the channel.
- 60 6. A process of reducing asphaltic base materials to refined asphaltum which includes the following steps in the order named, first, heating said base materials, second, allowing said materials to flow in a vertical thin film over a heated surface so that vapors may be driven therefrom, third, allowing the materials from which the vapors have been extracted to flow through a closed conduit, and fourth, allowing the materials to flow over the exterior of said conduit so that a further distillation takes place therefrom.
- 65 7. A process of reducing asphaltic base materials to refined asphaltum which includes the following steps in the order named, first, heating said base materials under pressure, second, releasing said pressure and allowing said materials to flow in a vertical thin film over a heated surface so that vapors may be driven therefrom, third, allowing the materials from which the vapors have been extracted to flow through a closed conduit, and fourth, allowing the materials to flow over the exterior of said conduit so that a further distillation takes place therefrom.
- 70 8. A process of reducing asphaltic base materials to refined asphaltum which includes the following steps in the order named, first, heating said base materials, second, allowing said materials to flow in a vertical thin film over a heated surface so that vapors may be driven therefrom, third, allowing the materials from which the vapors have been extracted to flow through a closed conduit, said materials being kept under some pressure in said conduit to pre- 75

vent the formation of vapors therein, and fourth, relieving the materials from said pressure in said conduit and allowing the materials to flow over the exterior of said conduit so that a further distillation takes place therefrom.

9. A process of reducing asphaltic base materials to refined asphaltum which includes the following steps in the order named, first, 10 heating said base materials under pressure, second, releasing said pressure and allowing said materials to flow in a vertical thin film over a heated surface so that vapors may be driven therefrom, third, allowing the materials 15 from which the vapors have been ex-

tracted to flow through a closed conduit, said materials being kept under some pressure in said conduit to prevent the formation of vapors therein, and fourth, relieving the materials from said pressure in said conduit 20 and allowing the materials to flow over the exterior of said conduit so that a further distillation takes place therefrom.

In testimony whereof, I have hereunto set my hand at Los Angeles, California, this 25 31st day of August, 1912.

MILON JAMES TRUMBLE.
